METHOD AND APPARATUS FOR MAKING
METAL CONTAINERSJohn F. Werder, Lakewood, Ohio, assignor of
one-half to Edmund Rogers, South Euclid,
Ohio

Application January 10, 1931, Serial No. 507,929

10 Claims. (Cl. 113—67)

This invention relates to the art of metal containers which are adapted to withstand substantial internal pressure.

The containers contemplated by the present invention may be employed for the storage, shipping, and dispensing of various fluids under pressure, either gas or liquid, and the present application is especially concerned with its use for a gas-charged liquid, such as a lubricant for automobiles. It is to be understood, however, that the method and apparatus herein disclosed may be employed for the construction of metal containers to be applied to any purpose for which they are adapted. It is to be understood also that the present form of disclosure is merely for purposes of illustration and that there may be devised various modifications without departing from the spirit of the present invention as herein described and claimed.

20 The purpose of filling such a container with a gas-charged lubricant or other liquid is to enable it to be discharged from the container by means of the pressure contained therein. This has proved especially advantageous in the use of such 25 a gas-charged lubricant upon automobiles.

In devising a container for fluid under substantial pressure, applicant has found it most expedient to give to the body and ends of the container as nearly as possible a form which it would 30 naturally take when subjected to such pressure. The tendency of such pressure, radially and equally in all directions, is towards a spherical form of container. The present invention therefore contemplates giving to the container so far 35 as practical in a cylindrical container now under consideration, a form determined by the degree of pressure which the container is intended to withstand. The application of air pressure to the inside of the container for this purpose is 40 known as the "blowing" process. The degree of pressure applied to the inside of such container may vary according to conditions as for instance by the length of time the container is subjected 45 to such pressure and also the gauge of the metal of the container body. In the comparatively small size of container which is formed of light sheet metal, as for instance, tin plate with which the present invention is primarily concerned, it has been found that 75 pounds air pressure is 50 sufficient for practical purposes, although such a container has been successfully charged to the point of 200 pounds. In any event, the pressure applied during the "blowing" process is considerably greater than that to which the container 55 is to be subjected by its contents.

Heretofore, in the manufacture of containers intended to withstand internal pressure, it has been the practice to first give the parts of the metal body their final form corresponding to that which they would naturally take under such internal pressure, and then solder the seams for holding the parts of the container body together. This practice has apparently been thought necessary and until the present invention, there has not been discovered the possibility of applying 10 flux and solder to the inside of the container for re-soldering the joints as would be required if the parts of the container should first be soldered together and then subjected to the internal pressure corresponding to that for which they are 15 intended. Obviously, after the parts of the container have all been soldered together, it is altogether impossible to inject flux or solder through these soldered joints for the purpose of re-soldering the same upon the inside of the container to 20 correct any fault or failure thereof during the "blowing" process.

Applicant however has devised a more expedient method of first applying and soldering the heads in plain form to the cylindrical body which 25 has already been connected along its longitudinal joint but without solder being applied thereto, assuming that the old form of side seam be employed. In such form, according to the present improved method, the container is subjected to 30 internal pressure so as to "blow" the heads of the container to the extent desired and to generally give proper curvature to the cylindrical body as 35 well. This method of procedure is made possible by the applicant's discovery and invention of a method of then re-soldering the inside of the 40 head joints so as to overcome any weakness due to the strain of the "blowing" process. If so desired, the longitudinal joint may have been 45 already soldered by the application of flux and solder thereto from the outside. This therefore constitutes the object of the present invention which includes both the method and apparatus 50 for carrying out the procedure referred to.

Fig. 1 illustrates the insertion of flux to the inside of the container; Figs. 2 and 3 illustrate the container in end and side views, respectively, as applied to the apparatus for re-soldering the head joints.

The means for introducing the flux and possibly 55 also solder to the inside of the container involves a small opening through the center of one of the heads of the container, through which the flux and solder may be introduced in any suitable manner and from any suitable form of container.

This particular step in the method is illustrated in Fig. 1, in which a supply of flux may be fed by gravity from the supply tank 1 through the pipe 2 and the hand-operated valve 3. When 5 the flux and solder have been thus inserted into the container, it will be placed upon the specially provided rollers in such position that the flux and solder will find their way by gravity to the region of the head joint at one end of the container. 10 10 The same process can then be repeated for the head joint at the other end.

The manner of construction and arrangement of the soldering rollers is indicated in Fig. 3 in which the larger rollers 4 and the smaller rollers 15 5 when arranged in such manner will permit the container 6 to assume inclined position. Rollers 4 and 5 are mounted upon the same shaft in each case. The rollers 5 will be heated in any suitable manner and will be supplied with solder 20 from the bath 7 into which the rollers 5 extend. The shoes 8 are provided at their upper corners with cut-out portions which are curved at their bottoms and are spaced slightly from the rollers 5 so as to permit a film of solder to be carried by 25 the rollers 5 from the bath 7 but without permitting the undesirable oxidized surface portion of the solder from being carried upwardly by the rollers 5. In this way, there is insured the application of only clean and efficient solder to the 30 joints.

As a means of insuring an efficient wiping action by the rollers 5 upon the joint of the container during the re-soldering operation, I have devised the method of operating the two rollers 35 5 at somewhat different speeds, these rollers in the present case being of the same size. There will thereby be caused a movement of the container about its axis as it rests upon the rollers 5 and there will be produced an efficient soldering 40 operation about the entire head joint as the container is rolled about.

Instead of having rollers 5 of the same diameter operated at different speeds, there may be substituted rollers of different diameters rotated 45 45 at the same speed. The gist of the invention is that there may be a difference in the linear or surface speed of the two rollers 5 so as to produce the wiping action.

In the present form of illustration, the belt 9 50 is driven from the sprocket 10 on the drive shaft 11 and has drive connection with the sprocket 12 on the shaft 13. The same shaft 13 through the sprocket 14 and the chain 15 drives the shaft 16 upon which one of the rollers 5 is mounted. 55 As will be seen from Fig. 2, as a result of the drive connections therein indicated, the rollers 5 will be driven at different speeds but in the same direction. It is to be understood that any other suitable form of mechanism as for instance gear 60 connections, may be adopted for the same purpose and that the ratio between the speeds of the rollers 5 may also be varied. As above stated, upon completion of the soldering operation for the joint at the one end of the container, the position 65 of the container upon the rollers 4 and 5 may be reversed so as to permit the same re-soldering operation for the other end head.

The small aperture in the one head of the container which has been employed for the introduction 70 of flux and solder to the inside of the container, may be utilized for the installation of a valve connection to be employed for the filling of the container with the gas-charged lubricant and later for the discharge of the same therefrom.

75 Thus, I have devised a comparatively simple

and yet effective method and apparatus for the re-soldering of the head joints from the inside of the container with the result that there is precluded the danger of leaks which are otherwise calculated to defeat the self-contained internal pressure as well as to lose the contents of the container. This invention also makes possible the construction of a container in the particular manner, as above outlined, which was apparently deemed impossible heretofore and which permits "blowing" the walls of the container to a form approaching as nearly as practical that corresponding to the force exerted by the internal pressure. Thus there is produced a more reliable form of container for the purposes intended.

What I claim is:

1. The method of making a metal container adapted to withstand substantial internal pressure, consisting in soldering together the body and heads of a metal container, subjecting the 20 interior thereof to a pressure corresponding approximately to the aforesaid internal pressure, and then re-soldering the joints between the body and heads of the container from the inside and outside thereof simultaneously.

2. The method of making a metal container adapted to withstand substantial internal pressure, consisting in soldering together the body and heads of a metal container, subjecting the 25 interior thereof to a pressure corresponding approximately to the aforesaid internal pressure, and then re-soldering the joints between the body and heads of the container from the inside and outside thereof simultaneously.

3. The method of making a metal container adapted to withstand substantial internal pressure, consisting in soldering together the body and heads of a metal container, subjecting the 30 interior thereof to a pressure corresponding approximately to the aforesaid internal pressure, and then re-soldering the joints between the body and heads of the container by the introduction of soldering material to the inside thereof and the application of soldering material to the outside thereof while the container is in inclined 35 position.

4. The method of making a metal container adapted to withstand substantial internal pressure, consisting in soldering together the body and heads of a metal container, subjecting the 40 interior thereof to a pressure corresponding approximately to the aforesaid internal pressure, and then re-soldering in succession the joints between the body and heads of the container by 45 the introduction of successive charges of soldering material to the inside thereof through an opening in one of the heads thereof and the application of heat to the restricted area of the joint being re-soldered.

4. The method of making a metal container adapted to withstand substantial internal pressure, consisting in soldering together the body and heads of a metal container, subjecting the 50 interior thereof to a pressure corresponding approximately to the aforesaid internal pressure, and then re-soldering in succession the joints between the body and heads of the container by the introduction of successive charges of soldering 55 material to the inside thereof and by then applying heat to the restricted area of each joint during rotation of the container body in an inclined position about its longitudinal axis.

5. In a device of the class described, the combination of pairs of rotatable heated rollers so arranged as to afford support for a cylindrical container, the rollers of one pair being of smaller diameter than those of the other pair so as to cause the container to assume a tilted position for 60 properly locating the soldering material therewithin at the head joint of the container, and means for rotating said rollers.

6. The method of making a metal container, including the soldering of the joints between the 75

body and heads of the container from the inside and outside thereof simultaneously.

7. The method of making a metal container, including the soldering of the joints between the body and heads of the container, by the application of soldering material to the inside of the joint and the application of soldering material to the outside of the joint simultaneously while the container is in inclined position.

10 8. In a device of the class described, the combination of means including rotatable heated rollers of different diameters arranged on the same axis at the two ends of the container for locating soldering material within the container 15 at the proper point within the same and for re-soldering the same, and means for operating said rollers.

9. In a device of the class described, the com-

bination of means including rotatable rollers for tilting the container so as to locate soldering material within the container at the proper end joint on the inside thereof and for applying soldering material simultaneously to the outside thereof so as to solder the same while in such tilted position, and means for applying solder to the soldering rollers.

10 16. In a device of the class described, the combination of rotatable heated roller means of different diameters arranged on the same axis and adapted to engage the ends of the container for tilting the same so as to locate soldering material within the container at the proper end joint and for soldering the same while in such tilting position, and means for operating the rollers.
